(74) **Attorney, Agent, or Firm:** FOLEY & LARDNER LLP

(57) **CLAIM**

The ornamental design for a label printer as shown and described.

DESCRIPTION

FIG. 1 is a front perspective view of a label printer, in accordance with a first embodiment;

FIG. 2 is a front view of the label printer of FIG. 1;

FIG. 3 is a rear view of the label printer of FIG. 1;

FIG. 4 is a top view of the label printer of FIG. 1;

FIG. 5 is a bottom view of the label printer of FIG. 1;

FIG. 6 is a right side view of the label printer of FIG. 1;

FIG. 7 is a left side view of the label printer of FIG. 1;

FIG. 8 is a front perspective view of a label printer, in accordance with a second embodiment;

FIG. 9 is a front view of the label printer of FIG. 8;

FIG. 10 is a rear view of the label printer of FIG. 8;

FIG. 11 is a top view of the label printer of FIG. 8;

FIG. 12 is a bottom view of the label printer of FIG. 8;

FIG. 13 is a right side view of the label printer of FIG. 8; and,

FIG. 14 is a left side view of the label printer of FIG. 8.

The broken lines immediately adjacent to the shaded areas depict the bounds of the claimed design, while all other broken lines are directed to environment. The broken lines form no part of the claimed design.

1 Claim, 14 Drawing Sheets
